United States Patent Office.

WESLEY W. HAMILTON, OF NEW YORK, N. Y., ASSIGNOR TO HIM
SELF AND W. G. VERMILYE, OF SAME PLACE.

Design No. 3,449, dated April 13, 1869.

DESIGN FOR AN ERASER.

The Schedule referred to in these Letters Patent and making part of the same.

To all whom it may concern:

Be it known that I, WESLEY W. HAMILTON, of the city, county, and State of New York, have invented a new and original Design for Rubber Eraser; and I do hereby declare that the following is a full, clear, and exact description thereof, which will enable others skilled in the art to make and use the same, reference being had to the accompanying drawings, forming part of this specification.

This invention relates to rubber, or compositions consisting of India rubber combined with other material or materials or substances, for erasing lead marks and ink marks, and to be used for all the purposes to which elastic erasers are adapted; and

The invention consists in making the eraser in the form of an equilateral triangle, of any desired size and thickness, and of any quality or grade.

In the accompanying drawings—

Figure 1 represents a top view of my eraser.

Figure 2 is an edge view of the same.

Similar letters of reference indicate corresponding parts.

The eraser is in form of an equilateral triangle. The sides of the eraser may contain any design or device,

printed, stamped, or moulded thereon, embracing the manufacturer's name, locality, or other information.

In this example of my invention, lines parallel with the sides of the triangle are, shown, enclosing the words, "Delta-Eraser," which is the name and designation by which my eraser is to be known.

I do not confine myself to any particular imprint or stamp surrounding the said lines, and the said lines and words enclosed thereby may be either raised or sunken on the side of the eraser, and of any desired shade or color, my object being to secure the form of an equilateral triangle as a design for an eraser.

Having thus described my invention,

What I claim as new, and desire to secure by Letters Patent, is—

A rubber eraser, or an eraser containing rubber, in the form of an equilateral triangle, substantially as and for the purposes herein described.

The above specification of my invention signed by me this 18th day of March, 1869.

WESLEY W. HAMILTON.
